UNITED STATES PATENT OFFICE

JOHN WILSON BROWN, JR., OF PHILADELPHIA, PENNSYLVANIA

ROTARY GANG DRILL

Application filed April 30, 1931. Serial No. 534,042.

This invention relates to rotary drilling or cutting machines, and more particularly to a machine for simultaneously performing a plurality of operations on a given article; as for example, drilling and then reaming the drilled openings of such articles.

An important object of the invention is the provision of apparatus of this character in which the articles upon which the operations are to be performed are so presented to the tools that an operation of one kind is performed upon one of the articles simultaneously with the performance of a second operation on another of the articles.

A still further object of the invention is the adaptation of an arrangement of this character to that type of rotary drilling machines illustrated in my prior patents in which work-holding devices and the drilling or cutting implements are simultaneously rotated about a common center and are caused to approach and recede from one another to bring the work into engagement with the tools.

A still further object of the invention is the provision of a novel and improved jig for use in conjunction with apparatus of this character.

These and other objects I attain by the construction shown in the accompanying drawings wherein, for the purpose of illustration, I have shown a preferred embodiment of my invention and wherein:

Fig. 1 is a vertical sectional view through a rotary drilling apparatus constructed in accordance with my invention;

Fig. 2 is a partially diagrammatic plan illustrating the distribution of the tables and drilling or cutting apparatuses about the carrier;

Fig. 3 is a section on line 3-3 of Fig. 1;

Fig. 4 is a section on line 4-4 of Fig. 3;

Fig. 5 is an enlarged vertical sectional view through one of the tables and one of the groups of tools associated therewith;

Fig. 6 is a fragmentary detail sectional view showing the work-positioning means; and

Fig. 7 is a section on line 7-7 of Fig. 5.

Referring now more particularly to the

drawings, the numeral 10 generally designates a suitable stationary standard, and rotatable thereabout a carrier 11. The standard mounts a cam 12 adjacent its lower end. Upon said cam are seated the lower ends of the stems 13 of a plurality of work tables 14, the cam acting through these stems to elevate the work tables and subsequently lower them as the carrier is rotated. The upper end of the carrier 11 mounts in alignment with each work table a spindle 15, the spindles 15 each having at their upper ends driving engagement with a gear 16 rotatably supported from the carrier. The upper end of the carrier further mounts a gear 17 which is secured thereto while the upper end of the standard 10 supports driving mechanisms for driving the gears 16 and 17 at different rates of speed with the result that the carrier is rotated and the spindles 15 are likewise rotated. The mechanism as generally described hereinbefore is disclosed in prior applications, including application Serial No. 494,432, filed November 8, 1930 for bossed arm drilling machine, and constitutes no part of the present invention, except in combination with the structure hereinafter described.

The mounting means for the spindles 15 comprises upper and lower flanges 18 and 19 projecting horizontally outwardly from the carrier and preferably forming a part of a removable head 20 for the carrier. In accordance with the present invention I secure against the lower flange 18 a casing 21 for each spindle 15, the upper end of the casing housing the lower end of the associated spindle and a gear 22 secured thereto. This casing further mounts gear elements 23 and 24 each including a part engaging gear 22 and a second part engaging gears 23-a and 24-a associated therewith. Gears 23-a and 24-a are secured to chuck spindles 25, the spindles of gears 23-a in the present instance mounting drills 26 and those of the gears 24-a mounting reaming and facing tools 27.

Associated with each casing 21 is a pair of vertically movable plates 28, 29, the plate 28 having guides 30 for the drills 26 while

the table 29 has guides 31 for the reaming and facing tools 27. Each plate 28 and 29 is mounted on a pair of guide rods vertically shiftable through the lower flange, one of these guide rods having associated therewith a stop nut 32 adjustable to limit downward movement of the associated plate by engaging the upper surface of flange 18 and a spring 33 for forcing the guide rod downwardly, these parts being similar to those employed in a similar location in the prior application hereinbefore referred to. The drill guides 30 of the plate 28 preferably include work-positioning elements 34 the construction and function of which will be hereinafter more fully set forth.

To each work table I secure a jig 35, this jig comprising a base 36 secured to the work table and having rotatably mounted therein a shaft 37 having at its lower end a head or enlargement 38 lying within a recess formed in the base. The upper surface of the head is provided with a circumferential series of sockets 39 for co-action with the spring-pressed positioning pin 40 mounted in the base whereby at selected rotatably spaced intervals the rotation of the shaft is checked and in an approximate position. The upper surface of the base is rabbeted to receive a plate 41, said plate having at the outer face of the base, or that portion thereof which is outwardly disposed as the carrier rotates, a notch 42 and at the inner face of the base pairs of openings 43 for the passage of the drills and the reaming elements of the reaming and facing tools. The base at this side thereof has a projecting ledge or flange 44 likewise provided with openings 45 for the passage of the drilling and reaming tools and for the passage of cuttings formed thereby.

Seating upon the upper surface of plate 41 and secured to the upper end of the shaft 37 as at 46 is a plate 47, said plate having formed therethrough a series of openings 48 each of sufficient size to loosely receive the article 49 upon which the operations are to be performed. In the present instance this article is disclosed as the bearing cap of a connecting rod and the opening is accordingly substantially rectangular, having at its ends recesses 50 to receive bosses projecting from the ends of the connecting rod cap, the outermost recess 50 being formed as a slot opening through the outer edge of plate 47. The outer edge of this plate is formed with a series of projecting shoulders 51, these shoulders being at present shown as continuations of the trailing walls of the notches. A shoulder 51 of this plate is radial, or substantially radial to the carrier whenever the pin 40 is engaged in a depression 39 of head 38. An index pin 52 stationary with relation to the standard 10 and 65 preferably carried by a shield or guard 53

surrounding the lower end of the carrier is arranged to engage the radially-directed shoulder 51 of each plate 47 as the carrier rotates and thus rotate the plate and advance the articles carried thereby one step.

Referring more particularly to Fig. 2 of the drawings, in the operation of the apparatus let it be assumed that the cam begins to elevate the tables 14 at the point indicated by the arrow "A" of Fig. 2, completes its elevation at the point indicated by the arrow "B" and completes lowering of the tables at the point indicated by the arrow "C". The operator station is indicated at O.S. and an operator disposed at this station drops an article 49 in the pocket 50 which has previously been aligned with notch 42 of plate 41 and from which, accordingly, the article previously held and upon which the operations have been completed, has fallen, this opening 48 having been again shifted to overlie the plate by the index pin 52 immediately after the lowering of the table has caused the same to clear the tools. Articles placed in the opening 48 are swept over the plate 41 by rotation of plate 47 and at each rotational step of plate 47 a new article is presented beneath the drills 26 and an article subsequently drilled is placed beneath the reaming and facing tools 27. As the table rises in response to the cam action, the first actual engagement between the articles and the drilling mechanism constitutes engagement of plates 28 and 29 with the articles. Engagement of plate 28 with the articles is through the positioning device 34 hereinbefore referred to, such positioning devices in the present instance comprising depending fingers arranged in two groups and adapted to co-act with the bossed end portions of the article and having beveled faces engaging such bossed end portions, these beveled faces centering the article so that the drills will be accurately positioned to form openings at the desired points.

It will be understood that after primary engagement of the plate 28 and positioning of the article, the plate yields through its spring action and elevates with the table 50 so that the drills finally engage the article to form openings therein. Plate 29, since the elements thereof embody reaming tools to engage in the openings formed by drills 26, needs no accurate positioning device for the articles, the tapering noses 27-a of the reamers performing the positioning function. In order to prevent chattering of the article when engaged by the reamers, however, the plate 29 is brought into direct engagement therewith. In the present instance the article has at its center a lug 49-a which engages the plate. After engagement with the lug, plate 29 will, of course, yield against its spring and rise with the table.

The engagement of the plates 28 and 29 with the articles serves not only to position the articles and prevent chattering thereof as hereinbefore stated, but likewise serves to 5 withdraw the articles from the drilling and reaming tools when separation of the tables and drilling or cutting mechanisms begins and to impart an initial downward movement to the tables, thus eliminating any tendency of the same to stick and not follow the cam as is otherwise possible. It will, of course, be understood that other types of cutting implements may be employed than those herein illustrated and it is to this end 10 that I prefer that the drilling and cutting mechanisms be detachably secured to the lower face of the flange 18 rather than incorporated in the head structure of the rotatable carrier. Construction in this manner will permit ready interchangeability of the drilling and cutting mechanisms, thus permitting the machine to be employed in a wide range of uses.

It will be obvious that if the cutting implements of either set completely perforate the article being operated upon as in the present construction, there is a tendency to form on the under surface of the article a burr which would be liable to catch on the edges of the openings through which the drills or other tools pass, and to cause a canting of the article so that the same might either jump from the pocket or opening in which it is disposed or be so positioned that 25 successive cutting tools would not properly operate upon the piece. I, accordingly, form in the upper surface of the plate 41 arcuate grooves 41-a having as their centers of curvature the axis of the perforated plate 30 40 47, these grooves extending in the direction of rotation of the plate 47 from the openings 43 for passage of the drills 26 to the notch 42. With the provision of these grooves any burr formed by the drills in passing through 45 the article will serve to assist in preventing shifting of the article rather than to cause such shifting.

Since the construction illustrated is obviously capable of a certain range of change 50 and modification without in any manner departing from the spirit of my invention, I do not wish to be understood as limiting myself thereto except as hereinafter claimed.

I claim:

55 1. In combination, a plurality of sets of rotary cutting implements grouped about and rotatable as sets about a common axis, non-rotatable work supports one for each set of cutting implements and each permanently aligned with a set rotatable about 60 said axis, each set of cutting implements comprising groups of different cutting implements means for rotating the sets of cutting implements and their associated tables about said axis, means for rotating the cut-

ting implements of the sets as the sets are rotated about said axis and means operating as an incident to rotation of the tables about said axis for shifting work positioned upon said tables upon the surface of the table as the table rotates about said axis to thereby successively present it to the groups of cutting implements comprising the set associated with the table.

70 2. In combination, a set of rotary cutting tools and an opposed non-rotatable work table, means for bodily rotating the set and work table about an axis, means for causing the work table to approach and recede from the cutting tools during rotation about said axis, said set of cutting tools comprising groups of cutting tools of different characteristics and means operating as an incident to rotation of the table about said axis for shifting work upon the work table to successively present it to said groups of cutting tools in approximate alignment therewith, and means operating as an incident to approach of the work table and cutting tools 75 for accurately aligning the work with the cutting tools.

80 3. In combination, a rotatable carrier having a flange, a spindle rotatably mounted in the flange, means for rotating the carrier, means for rotating the spindle, a unit detachably secured to the under surface of the flange, a plurality of rotatable cutting tools carried by said unit, means providing a driving connection between the spindle and the unit and a work table opposing the unit and approaching and receding therefrom as the carrier rotates.

85 4. In combination, a rotatable carrier, a table rotating with the carrier, means for elevating and lowering the table as the carrier rotates, a work support mounted upon the table and including a member to receive articles to be operated upon and a member rotatable upon said article-receiving member and having openings through which articles may be placed upon the surface of the article-receiving member, rotary cutting means carried by the carrier for engagement with articles mounted upon the article-supporting member and means operating as an incident to rotation of the carrier for imparting one step of a step-by-step rotation to the rotatable member each time the articles carried by said member are disengaged from said cutting tools.

90 105 110 115 120 125 130 5. In combination, a carrier, a table rotating with the carrier, means for elevating and lowering the table as the carrier rotates, a work support mounted upon the table and including a member to receive articles to be operated upon and a member rotatable upon said article-receiving member and having openings through which articles may be placed upon the surface of the article-receiving member, rotary cutting means carried

by the carrier for engagement with articles mounted upon the article-supporting member, means for imparting a step-by-step rotation to the rotatable member while the articles carried by said member are disengaged from said cutting tools, the openings of said rotatable member permitting limited shifting movement of articles disposed therein and yieldable means carried by the carrier and engaging the articles prior to the engagement of said cutting tools therewith for disposing said articles in predetermined positions in the opening.

6. In combination, a plurality of sets of rotary cutting implements grouped about and rotatable about a common axis, work supports one for each set of cutting implements and each aligned with a set, said work supports being rotatable about said axis, and held against rotation on their own axes, each set of cutting implements comprising different cutting implements, means for rotating the sets of cutting implements and their associated tables about said axis, means for 25 rotating the cutting implements as the sets are rotated about said axis and means for shifting work positioned upon said tables upon the surface of the table as the table rotates about said axis to thereby successively 30 present it to the cutting implements comprising the set associated therewith.

7. In combination, a set of rotary cutting tools and an opposed non-rotatable work table, means for bodily rotating the set and work table about an axis, means for causing the work table to approach and recede from the cutting tools during rotation about said axis, said set of cutting tools comprising cutting tools of different characteristics and 40 means operating as an incident to rotation of the work table about said axis for shifting work upon the work table to successively present it to said cutting tools.

8. In combination, a rotatable carrier having a flange, a spindle rotatably mounted in the flange, means for rotating the carrier, means for rotating the spindle, a unit detachably secured to the under surface of the flange, a plurality of rotatable cutting tools 50 carried by said unit, means providing a driving connection between the spindle and the unit, a non-rotatable work table opposing the unit and approaching and receding therefrom as the carrier rotates, said rotatable cutting tools including groups of tools, said groups being of different characteristics and the tools of each group being of the same characteristics, and means associated with the work table and operating as an incident to rotation of the carrier for shifting an article disposed thereon for successive engagement by said groups.

9. In combination, a rotatable carrier, a table rotating with the carrier, means for 65 elevating and lowering the table as the car-

rier rotates, a non-rotatable work support mounted upon the table and including a member to receive articles to be operated upon and a member rotatable upon said article-receiving member and having openings through which articles may be placed upon the surface of the article-receiving member, rotary cutting means carried by the carrier for engagement with articles mounted upon the article-supporting member and means operating as an incident to rotation of the carrier for imparting a step-by-step rotation to the rotatable member while the articles carried by said member are disengaged from said cutting tools, said rotary cutting means including groups of tools of different characteristics, the rotation of the rotatable member shifting the articles through a distance equal to the distance between adjacent groups at each step.
